CLAIM

The ornamental design for a shoe sole, as shown and described.

DESCRIPTION

FIG. 1 is a bottom plan view of a shoe sole showing my new design, the side opposite that shown in FIG. 1 being plain and unornamented;

FIG. 2 is an enlarged fragmentary cross sectional view on the line 2—2 of FIG. 1;

FIG. 3 is a side elevational view thereof from the bottom of FIG. 1; and,

FIG. 4 is a side elevational view thereof from the right of FIG. 1.
